CLAIM

The ornamental design for a housing for drone parachute, as shown and described.

DESCRIPTION

FIG. 1 is a front view of a housing for drone parachute of my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a first perspective view showing a use state thereof; and,

FIG. 9 is a second perspective view showing a use state thereof.

The broken lines shown in the figures form no part of the claimed design. The alternate long dashed short dashed line disclosed in the figures is a boundary line and forms no part of the claimed design.

1 Claim, 8 Drawing Sheets
